UNITED STATES PATENT OFFICE.

JAMES RICHARD HARGIS, OF SPRINGFIELD, MISSOURI.

AUTOMATIC BROODER.

1,266,462.

Specification of Letters Patent. Patented May 14, 1918.

Application filed June 15, 1917. Serial No. 174,986.

To all whom it may concern:

Be it known that I, JAMES R. HARGIS, a citizen of the United States, residing at Springfield, in the county of Greene and 5 State of Missouri, have invented new and useful Improvements in Automatic Brooders, of which the following is a specification.

This invention relates to brooders for use in raising young chicks in large numbers 10 without the aid of a hen.

The primary object of the invention is to construct a brooder capable of being automatically closed when the number of fowls therein reaches a predetermined weight, so 15 that crowding and suffocation thereof will be prevented and the housing conditions maintained in a more sanitary manner.

A further object of the invention is to provide means whereby the automatic closing of the brooder may be regulated, so that 20 the said brooder may be used to accommodate a various number of fowls, the automatic closing means being set so as to close the brooder when the number of fowls therein reaches a predetermined weight.

With the above stated and other objects in view, the invention consists of a receptacle provided with an opening, which is adapted to be closed by means of a sliding 30 closure, which is flexibly connected to the rotatably mounted drum upon which the connection is adapted to be wound for the purpose of maintaining the receptacle in an open condition to permit the entrance and 35 exit of the chicks. The invention further includes a movable bottom for the receptacle, which is connected to a rotatable drum in a manner to permit of its automatic release when the number of fowls therein reaches a predetermined weight.

In carrying out the objects of the invention, it is understood that various changes may be made in the practical embodiment thereof and the right is reserved to make 45 such changes, the preferred form of the invention being illustrated in the accompanying drawings, in which—

Figure 1 is a perspective view of a brooder embodying the present invention.

Fig. 2 is a vertical longitudinal sectional view of the same with the door open.

Fig. 3 is a similar view showing the parts in position when the door is closed.

In the proper embodiment of the invention hereinafter shown, there is illustrated a receptacle 10, of suitable form and dimen-

sions, the said receptacle being preferably of rectangular form in plan view and including a top 11, sides 12 and front and rear walls 13 and 14 respectively.

60

The front wall of the receptacle is provided with an entrance opening 15, for the purpose of providing means for the entrance and exit of chicks. This opening is adapted to be closed by a slide 16, which is mounted 65 for vertical sliding movement in guides 17 arranged upon each side of the opening 15.

Mounted upon the front of the receptacle is a drum 18, whose pintles 19 are mounted for rotation in brackets 20 secured near the 70 upper edge of the front wall 13. This drum is connected to the slide 16 by means of flexible connections 21, each having one of their ends secured to and wound upon the drum 18 and their opposite ends secured to 75 the slide 16 by means of staples 22 or analogous fastening devices.

The drum 18 carries a radially extending member 23, secured approximately centrally thereof and mounted upon the top 11 of the 80 receptacle is a lever 24, which is provided with a hook end 25, which is adapted to be brought into the path of movement of the member 23 and engaged therewith for the purpose of preventing rotation of the drum. 85

The lever 24 is pivotally mounted upon the top 11 as shown at 26, the end of the lever opposite the hook 25 having secured thereto a cable or other element 27, by means of which it is connected to the bottom 28 of 90 the receptacle as shown at 29.

The bottom 28 is mounted for sliding movement within the receptacle 10, the length of the cable 27 being such that when the hook 25 is engaged with the member 23 95 of the drum, the said bottom will be slightly elevated, the drum having first been rotated sufficiently to raise the slide 16 above the opening 15 to permit access to the interior of the brooder. When the parts are in position the weight of the chicks entering the brooder in sufficient number to produce the predetermined weight will cause the bottom 28 to be depressed, carrying with it the rear end of the lever 24, and disengaging the 105 hook end 25 from the member 23, permitting the rotation of the drum under the weight of the slide 16, the length of the flexible connection 21 being sufficient to permit said slide to close the opening 15.

100

In order to accurately adjust the brooder so that the entrance opening will be closed

110

when enough chicks to produce the desired weight have entered the brooder, the lever 24 is provided with an adjusting weight 30, which is slidably mounted thereon and is 5 adapted to be held in adjusted position by means of the set screw 31, the said weight being moved along the lever so that the bottom 28 will be lowered only after the combined weight of the desired number of 10 chicks has been placed thereon.

By this means any desired number of brooders may be utilized for the care of a large number of chicks, each brooder automatically closing to prevent the entrance of 15 any chicks above the number sufficient to produce the required weight, thereby preventing crowding and possible danger to the chicks.

Copies of this patent may be obtained for five cents each, by addressing the "Commissioner of Patents, Washington, D. C."

Having described the invention, what is claimed is:

A brooder comprising a receptacle provided with an opening, a slidable gravity closure therefor, a drum mounted for rotation above said sliding gravity closure, a flexible element having one end secured to 25 the closure and its opposite end wound around said drum, a radially extending lug carried by said drum, a vertically moving bottom for said closure and a pivoted lever located in the path of said lug and connected 30 to the bottom, whereby a downward movement of said bottom will release the lug and permit the rotation of the drum and the closing of the opening.

In testimony whereof I affix my signature. 35
JAMES RICHARD HARGIS.
